UNITED STATES PATENT OFFICE.

WILLIAM A. ALLEN, OF NEW YORK, N. Y.

ATTACHMENT MEANS FOR CONTROLLING APPARATUS.

Application filed November 9, 1926. Serial No. 147,293.

This invention relates to an attachment means used for supporting control apparatus, a control device associated with apparatus situated at a distance from the place where the attachment means are mounted. The attachment means to be described herein is particularly suitable for use on automotive vehicles, and when so used is attached to the dash board, or as the same is sometimes termed the cowl or instrument board.

The control element associated with the attachment means is used in connection with a shutter front placed in front of the radiator, or it may be used in connection with the engine carburetor for operating the choke thereof, or the device may be used for the control of other apparatus as desired.

Heretofore in the mounting of control rods for the carburetor and shutter fronts of radiators, etc., it has been necessary to drill a hole through the cowl, but since the part illustrated in the drawing is made of metal, usually steel, this entails considerable work, particularly where such devices are mounted as accessories, after the vehicle has gone into the hands of a user.

It is the principal object therefore of my invention to provide attachment means for supporting a control element to be used as described, which is easy to make and which can be quickly applied.

Other objects will be apparent after a study of the following specification.

My invention is illustrated in the annexed drawing wherein Figure 1 is a side elevation of the attachment means as applied to the dash or cowl of automotive vehicles which part is shown in section, and the control rod being placed in one position of operation.

Figure 2 is a front view of Figure 1 with the control rod withdrawn from the attachment means.

Figure 3 is a perspective view of the control rod shown in Figure 1.

Figure 4 is a fragmentary view of a modified form of attachment means.

Figure 5 is a still further modified form, while

Figure 6 is a further modified form of one of the clamps comprising the attachment means.

Referring now to the details, wherein like numbers refer to corresponding parts in the various figures, 1 represents the dash or cowl of the vehicle. In many such devices

the dash or cowl is bent away at the lower part, away from the driver's seat as illustrated by the part 2, and in some cases, the back of the cowl 1 is reinforced by a wood strip 24, as shown in Figure 5. By bending the part 2 backward as indicated the cowl is materially strengthened. I use this portion of the cowl to apply an attachment device, for such uses as may be required. As shown in Figure 1, the attachment means comprises a clamp 3, extending upward a short distance over the front face of the cowl 1, and a second clamp 4 having an end 5 bent or formed so as to slip over the edge 2 of the member 1, both clamps 3 and 4 having a hole therethrough to receive a hollow sleeve. The sleeve 6 is externally threaded and on one end, is preferably rigidly fastened, to the sleeve, a hexagonally shaped nut 7. The sleeve 6 is adapted to pass through the holes in the clamps 3 and 4, a facing washer 8 being preferably used between the nut 7 and the clamp 3. Back of the clamp 4 is another securing member in the form of a nut 9, which on being turned up, draws the clamps 3 and 4 together, thereby gripping the member 1, including the part 2, as will be clearly understood by reference to Figure 1.

The nut 7 is constructed so as to have a projecting part 10 preferably made in the form shown in Figure 2.

The projection 10 extends beyond the inner periphery of the bore through the sleeve 6.

Carried by the sleeve 6 is a control rod 11 having a part cut away, leaving a flat side 12, which when placed adjacent the projection 10 allows the control rod to be moved longitudinally of the sleeve 6. The rod 11 is provided with a plurality of circumferential grooves 13. These grooves are placed longitudinally of the rod 11 and as will be seen by Figure 3, run into the cutaway portion 12. The grooves 13 are adapted to cooperate with the projection 10, which in thickness is less than the width of the groove 13, whereby the control rod 11 by means of the thumb nut 14, may be turned so that the control rod is locked in different longitudinal positions as determined by the groove which is turned in to engage with the projection 10, it being understood that the grooves 13, extend only partially around the rod 11, that is to say beginning with the flat portion 12, the grooves taper in depth toward the outer circumferences of the rod.

As shown in Figure 1 the control rod 11 is shown partially withdrawn from the sleeve 6. The end of the control rod 11 is preferably formed to leave a tongue 15, having a hole 16 therein. The hole 16 is adapted to receive a wire or flexible cable which extends from the control rod to the lever on the radiator shutter front, or to a carburetor or other piece of apparatus that is to be operated.

As shown in Figure 1, a spacing washer 17 may be used between the clamps 3 and 4, when the length of the portion 2 of the cowl is greater than that for which the portion 5 of the bracket 4 is constructed.

It is obvious that the clamp 4 may be integrally made to fit any special case, or variations may be taken up by one or more spacing washers 17, which may or may not be required depending on circumstances.

Variations in the width of the portion 2 of the cowl may also be taken care of by the construction shown in Figure 4, in which there is associated with the bent over portion 5 of the clamp 4, an arm 18. The arm 18 may be slotted longitudinally as indicated by the dotted lines 23 and held to the portion 5, by any satisfactory means, as by screw 19, and nut 20. This construction allows the arm 18 to be moved forward or backward to accommodate various lengths of the portion 2.

It is obvious that the portion 5, may be slotted instead of the arm 18 to obtain the same result.

Where a wood strip 24 is used back of the cowl 1, the construction of the clamp 4 may be used as indicated in Figure 5, in which the portion 5 is bent upward along the edge of the wood strip and preferably has an indentation 21, to grip into the wood. Or the clamp 4 may have the end 5, formed as shown in Figure 6, so that the upper edge of the portion 5 will grip into the wood.

In the form shown in Figures 4 and 5 the clamps 3 and 4 may be drawn together by means separate from the sleeve 6 as by screws 22, and then the sleeve 6 may be attached to either one or both of the clamps 3 and 4 in any satisfactory manner, as by being mounted through holes in the clamp as indicated by the dotted lines 25.

From what has been said it will be readily understood that the details for carrying my invention into practice may be varied, without departing from the spirit of my invention or the scope of the appended claims.

Having thus described my invention, what I claim is:

1. An attachment device of the class described, comprising a pair of clamping members extending on opposite sides of a support, an externally threaded hollow sleeve passing through said clamping members and entirely supported thereby, a pair of nuts

on the sleeve for drawing the clamping members toward each other to grip the support, a control rod slidably carried by the sleeve, and means associated with one of said nuts comprising an integral part thereof and said rod for holding the rod in different operative positions. 79

2. An attachment device of the class described, comprising a pair of clamping members extending on opposite sides of a support, an externally threaded hollow sleeve passing through said clamping members, a pair of nuts on the sleeve for drawing the clamping members toward each other to grip the support, a control rod slidably carried by the sleeve, the outer of said nuts having a projection extending beyond the inner wall of the sleeve, said rod being formed so it can only be moved longitudinally of the sleeve when in one position, with respect to said projection and a plurality of circumferentially arranged grooves longitudinally spaced along the rod to cooperate with said nut projection on rotary movement of the rod, to lock the rod in different operative positions. 83

3. An attachment device of the class described comprising; a pair of clamping members extending on opposite sides of a support, a threaded hollow sleeve passing through said clamping members, means carried on the sleeve threads for drawing the clamping members toward each other to grip the support, a control rod passing through the sleeve, said rod having a part cut away longitudinally of its length and a plurality of circumferentially arranged grooves longitudinally spaced and running into said cut away portion and said sleeve having means associated therewith to cooperate with the cut away part of the rod and said grooves to allow the rod to be moved longitudinally of the sleeve when in only one rotary position and then locked by rotary movement of the rod when any one of said grooves is in alignment with said sleeve means. 100 105 110

4. An automobile dash control attachment means comprising, a clamp extending over the face of a dash member, a second clamp having a part to hook over the lower rear edge of the dash member, a hollow sleeve passing through said clamping members, adjustable means carried on the sleeve for drawing the clamps toward each other to grip the dash member, a control rod passing through the sleeve and means cooperating between the rod and part of the means for drawing the clamps together, for holding the rod in different longitudinal positions. 115 120 125

5. An attachment for the dash board of an automotive vehicle comprising; means for carrying a movable control element, a pair of clamps each independently constructed separate from said carrying means, one of said clamps being adapted to engage the 130

front face of the dash board and the other clamp having a part formed to engage the rear of the dash board, means for drawing said clamps toward each other to grip the dash board, at least one of said clamps extending far enough below the dash board to support thereon said carrying means.

6. An attachment for the dash board of an automotive vehicle comprising; a clamp 10 for engaging the front face of said dash board, a second clamp having a part for engaging the rear of the dash board, means positioned below the edge of the dash board for drawing said clamps toward each other 15 to grip the dash board and means for carrying a movable control element on at least one of the clamps.

7. An attachment for the dash board of an automotive vehicle; comprising, a clamp for 20 engaging the front face of said dash board, a second clamp having a part for engaging the rear of the dash board, means positioned below the edge of the dash board for drawing said clamps toward each other to grip the dash board, a sleeve supported by at least 25 one of said clamps and a movable control element carried by the sleeve.

8. An attachment for the dash board of an automotive vehicle comprising; a clamp for 30 engaging the front face of said dash board, a second clamp having a part for engaging

the rear of the dash board said part being adjustable for the purpose described, means for drawing said clamps toward each other to grip the dash board and means supported by at least one of the clamps for carrying a movable control element.

9. An attachment for the dash board of an automotive vehicle comprising; a clamp for engaging the front face of said dash 40 board, a second clamp having a part for engaging the rear of the dash board, a separate arm adjustably carried on said part for the purpose described, means positioned below the edge of the dash board for drawing said clamps toward each other to grip the dash board and means for carrying a movable control element on at least one of the clamps.

10. An attachment device of the class described comprising; a clamp extending over the lower face of a dash member, a second clamp extending over the lower rear part of the dash member, a hollow sleeve member passing through said clamping members below the dash and entirely supported by said clamping members, means carried on the sleeve for drawing the clamping members toward each other to grip the dash member and a control rod operatively carried by the sleeve.

In testimony whereof, I affix my signature.
WILLIAM A. ALLEN.
